(57) **CLAIM**

We claim the ornamental design for a handle configuration, as shown and described.

DESCRIPTION

FIG. 1 is a top-right side perspective of a handle configuration of the present invent;

FIG. 2 is a right-side elevational view thereof;

FIG. 3 is a left-side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines shown in FIGS. 1-7 illustrate portions of the handle configuration that form no part of the claimed design. The dash-dot lines shown in FIGS. 1-7 illustrate the bounds of the claim and form no part of the claimed design.
